UNITED STATES PATENT OFFICE.

FRANK MORRILL LOVERING, OF BANGOR, MAINE.

SPRING BED-BOTTOM.

1,148,341.

Specification of Letters Patent. Patented July 27, 1915.

Application filed November 5, 1914. Serial No. 870,329.

To all whom it may concern:

Be it known that I, FRANK MORRILL LOVERING, a citizen of the United States of America, and a resident of Bangor, in the county of Penobscot and State of Maine, have invented certain new and useful Improvements in Spring Bed-Bottoms, whereof the following is a specification.

This invention relates to spring bed bottoms of the link and plate type of fabric connected to the frame by horizontal coiled springs.

The principal object of the invention is to avoid sagging at the center of the mattress or bed bottom without interference with a proper elasticity thereof.

Figure 1 of the accompanying drawings represents a plan of a plate link and spring bed bottom containing an embodiment of this invention, parts thereof being broken out for convenience of illustration. Fig. 2 represents on a larger scale a longitudinal section through portions of said bed bottom on line 2—2 of Fig. 1. Fig. 3 represents on a still larger scale a transverse section through the central portion of said bed bottom near one end thereof on line 3—3 of Fig. 1, looking toward the left. Fig. 4 represents on the same scale as Fig. 3 a transverse section through the central strands of said bed bottom at about midway thereof on line 4—4 of Fig. 1, looking toward the left.

The same reference numbers indicate corresponding parts in the different figures.

The bed bottom herein shown to illustrate the preferred embodiment of this invention comprises two end angle bars 10 and 15 which constitute the frame. These angle bars are of the usual construction, their horizontal flanges being provided respectively with a series of holes 12 and a series of holes 17 for connection of the springs therewith. In this construction the end bar 10 is further provided with a supplemental central hole 13 and the end bar 15 with a supplemental hole 18.

The body of the spring bed bottom in the embodiment referred to is composed of two similar link and plate sections 20 and 30 disposed side by side somewhat apart from each other. Two rows 40 and 50 of horizontal coiled wire springs connect opposite ends of both the sections 20 and 30 with the angle bars 10 and 15.

The section 20 comprises an outer selvage warp strand 21, an inner selvage warp strand

22 and a plurality of intermediate warp strands 23. Each of the warp strands 21 and 22 is composed of plates 25, preferably of the usual triangular construction having three holes, and wire links 26 of the usual construction disposed longitudinally and provided with hooks at their opposite ends engaging said plates. The intermediate warp strands 23 are composed of plates 27, preferably of the usual square construction having four holes, and similar wire links 28 disposed longitudinally. The transverse or weft strands are formed in the usual manner by similar transverse links 29 disposed transversely and connecting laterally the plates of the warp strands.

The section 30 in said embodiment is of similar construction to the section 20 having an outer selvage warp strand 31, an inner selvage warp strand 32, and intermediate warp strands 33. The triangular plates 35, square plates 37, and links 38 and 39 correspond to those of the section 20.

The springs 41 and 51 of the rows 40 and 50 are in alinement with the warp strands and are directly connected therewith and alternate springs 42 and 52 of said rows are disposed between said alined springs and indirectly connected with said warp strands by means of V-shaped wire links 43 and 53 in a known manner.

The main sections 20 and 30 are connected by a variably expansible middle section composed of rigid parts or links disposed between and connecting the two main sections. This middle section thus constructed maintains an even surface with the connected sections and permits variable spreading of the latter to provide individual independence thereof. This middle section is composed in the illustrated embodiment of diagonal rigid links pivoted at their opposite ends to said main sections respectively. These links are inclined or arranged diagonally preferably in opposite directions and they may be arranged to cross each other in pairs. As shown the links 60 are parallel at one incline and the links 65 are parallel at a reversed incline, the links of each pair crossing each other about midway between the adjacent selvage strands 22 and 32 of the respective main sections. These diagonal links may be of the same construction as the longitudinal and transverse links heretofore referred to, and by arranging the inner selvage strands of the sections 20 and 30 some-

- what nearer than the other warp strands are to one another, these crossed links may be of the same length as the other links. The first pair of diagonal crossed links 60 and 65 next to the end bar 10 connects springs 41 of selvage strands 22 and 32 with the first triangular plates of said strands, and the second pair of diagonal crossed links 60 and 65 connects said first triangular plates with the second triangular plates of said strands, and so on. This diagonal arrangement of the links of the middle connecting section permits more or less lateral expansion and contraction and this lateral expansibility is variable throughout the length of the middle section and also varies in different parts thereof, being greater at the center and tapering therefrom toward the ends of the bed bottom.
- 20 A reinforcing elastic center rod 70 is disposed in the space between the main sections 20 and 30 in engagement with the intermediate connecting section and extends from end to end of the bed bottom. This center rod is preferably constructed of several parts, as for instance, a central part 73 and end parts 75 and 76. The central part 73 may be composed of one piece or link of wire having eyes 71 and 72 and the end parts 75 and 76 may be composed of coiled springs connecting the opposite ends or eyes 71 and 72 of said center part with the central holes 13 and 18 of said end bars. These springs constituting elastic end members of said rod are preferably somewhat longer than the springs of the warp strands and the coils thereof may be larger than the coils of said warp strand springs. This center rod passes under some of the diagonal links 60 and 65 and over the others, preferably at the crossing points thereof. In the preferred form as shown in Figs. 1 and 2, two pairs more or less of the crossed links at the center pass under the rod 70 and the other groups of diagonal links rest on said rod. This construction connects the center rod and the bed bottom so that they rise and fall in unison.
- 50 A bed bottom embodying this invention is reinforced against sagging at the center and yet has the required elasticity. The variably expansible middle section composed of rigid links disposed between and connecting the two main sections secures a uniform

surface throughout and permits the main sections to act independently of each other.

I claim as my invention:

1. In a bed bottom the combination of end bars, two body sections disposed side by side apart from each other, end springs connecting said body sections with said end bars, diagonal links connecting said sections, and an elastic center rod disposed between said sections and engaging said diagonal links.

2. In a bed bottom the combination of end bars, two body sections disposed side by side apart from each other, end springs connecting said body sections with said end bars, diagonal links connecting said sections, and an elastic center rod disposed between said sections and interwoven with said diagonal links.

3. In a bed bottom the combination of end bars, two body sections disposed side by side apart from each other, end springs connecting said sections with said end bars, diagonal crossed links connecting said sections, and an elastic center rod disposed between said sections and running under pairs of said crossed links and over other pairs thereof.

4. In a bed bottom the combination of two elastic body sections disposed side by side apart from each other, means for supporting such body sections, and a non-elastic laterally and variably expansible connecting means between said body sections, said connecting means being composed of rigid parts severally adjustable automatically and independently to a varying spread between said body sections.

5. In a bed bottom the combination of two elastic body sections disposed side by side apart from each other, means for supporting such body sections, and a non-elastic laterally and variably expansible connecting means between said body sections, said connecting means being composed of rigid parts severally adjustable automatically and independently to a varying spread between said body sections, and an elastic center rod disposed between said sections and engaging said connecting means.

FRANK MORRILL LOVERING.
